UNITED STATES PATENT OFFICE

GEORGE F. MATTESON, OF ROCKYHILL, CONNECTICUT, ASSIGNOR TO THE F. B. SHUSTER COMPANY, OF NEW HAVEN, CONNECTICUT, A CORPORATION OF CONNECTICUT

WIRE-STRAIGHTENING MACHINE

Application filed March 3, 1927. Serial No. 172,332.

My invention relates to the class of machines above named, and an object of my invention, among others, is to provide a machine of this kind that shall be simple in construction, one having means for conveniently changing or renewing parts and one that shall be particularly efficient in operation.

One form of machine embodying my invention and in the construction and use of which the objects herein set out, as well as others, may be attained, is illustrated in the accompanying drawings, in which—

Figure 1 is a top view of my improved wire straightening machine.

Figure 2 is a side view of the same.

Figure 3 is a detail view, scale enlarged, illustrating the construction of the feed rolls.

Figure 4 is a view in cross section on a plane denoted by the dotted line 4—4 of Figure 3.

In the accompanying drawings the numeral 6 indicates the base of my improved machine upon which certain units comprising operative parts of the structure are removably mounted, and from which base these units, each in its entirety, may be readily removed and as readily replaced, thereby enabling the machine to be quickly changed for any purpose that may be desired, or for purpose of renewal or repair of parts, the construction of said units to enable such removal or change to be more specifically hereinafter described, it being now briefly stated that said units comprise a breaker unit 7, a straightening unit 8, and a wire feeding unit 9.

A driving shaft 11 is mounted on the base and it is driven as by means of a pulley 12 secured thereto. A train of gears 13 connects the shaft 11 with the straightening unit to drive the latter, and a train of gears including a worm wheel 14 connects the shaft 11 with the breaker unit 7 for the purpose of driving the latter.

A worm 15 secured to the driving shaft meshes with a worm wheel 16 fast to a feed operating shaft 17 rotatably mounted in a frame 18 of the feed unit, and as shown in Figure 4 of the drawings. A gear 19 secured

to the shaft 17 meshes with a gear 20 on a lower feed roll shaft 21. The gear 19 also meshes with a gear 22 secured to an upper connecting shaft 23, which shaft has another gear 24 meshing with a gear 25 on a feed roll shaft 26, the shafts 21 and 26 each having a feed roll 27 or 28 secured thereto.

The gear 19 meshes with a gear 29 on a lower feed roll shaft 30, and the gear 24 meshes with a gear 31 on an upper feed roll shaft 32, each of which shafts are rotatably mounted in the frame 18. The shafts 26 and 32 are mounted in bearing blocks 33—34 adjustably located in openings in the frame 18, springs 35 exerting pressure upon said blocks to force them upwardly against tensioning screws 36 fitting screw threaded holes in a cap 43 on the frame, as shown in Figure 4. The lower ends of said screws about 70 against steps 37 seated upon resilient material, as rubber, and the upper end of said screws have adjusting gears 38 secured thereto and meshing with an adjusting pinion 39 on an adjusting sleeve 40 rotatably mounted on a pin 41 secured to and rising from the cap 43 on the frame 18, said sleeve 40 having an adjusting wheel 42 secured thereto as a means of operating the parts to release the blocks.

There is a set of adjusting members 80 appurtenant to each shaft 26 or 32 and comprising the parts just hereinabove described. There is also a set of feed rolls secured to the shafts 30 and 32, as hereinbefore described with respect to the feed rolls 27—28. 85

From this construction it will be observed that the shafts 26 and 32 may be raised or lowered to regulate the grip of the feed rolls upon a wire or wires. The movement of these rolls for all practical purposes will not be to 90 an extent to affect the efficiency of meshing of the gear 22 with the gears 25 and 31, said gears being arranged to permit the adjusting movement of the gears 25 and 31 equally on opposite sides of a plane passing through the axes of said gears and that of the shaft 23.

An important feature of the invention resides in locating the gears 25 and 31 out of line with the gears 20 and 29, so that the adjusting movement of said gears 25 and 31 may 100

be unlimited so far as the gears 20 and 29 are concerned.

The frame 18 constitutes a housing which is substantially closed as to its side walls to a point above the shafts 21 and 30, in the present case the top of the housing being closed by the cap 43, the housing being, therefore, substantially a closed structure so far as outflow of oil is concerned and, therefore, sufficient to contain oil in suitable amounts for lubricating purposes.

The bearings for the driving shaft 11 are located in a trough 44 projecting from one side of the housing 18 and a cap 45 is removably secured at one side of the housing over said trough to form an oil inclosure for lubricating the worm wheel 16 and the worm 15.

The housing or frame 18 has its base formed with an angular recess 46 shaped to fit the side of the base 6, and it is removably secured to the base as by means of threaded bolts, or otherwise as may be desired.

The shaft 26 is mounted in bearing blocks 33 slidably mounted in openings in opposite walls of the frame or housing 18, and the same is true of the shaft 32, this structure having been hereinbefore referred to. It will be noted that these bearing blocks have flanges 47 that close the openings 48 in which the blocks are located, these flanges extending far enough on opposite sides of the blocks to maintain the openings 48 in a closed condition in different positions of adjustment of said blocks within said openings.

The breaker and straightening units, as hereinbefore mentioned, are removably secured to the base 6, as by means of bolts 49 projecting through flanges in the bases of said unit into the base 6. Guide blocks 50 are secured in grooves in the under side of each of said bases, these guide blocks projecting into a groove 51 extending lengthwise in the base 6.

Persons skilled in the wire working art are acquainted with the fact that when a supply of wire being fed, from a spool of wire, to a rotating arbor type of wire straightener is about exhausted and the distorted and bent tail end of the wire leaves the said spool, a vigorous whipping of the end of the wire takes place. This is very objectionable and is due to the great amount of friction exerted upon the wire by the rotating arbor.

Applicant has discovered that this whipping action can be overcome entirely by placing at one end of the arbor a plurality of parallel pairs of feed rolls. These rolls will act to feed the wire through the arbor and will prevent its turning. It is very important that at least two pairs of closely positioned feed rolls be employed for a single pair of feed rolls at one or both ends of a rotating arbor wire straightener, as commonly used at this time, will not effect the desired result.

It will be noted that applicant has provided the two pairs of feed rolls, carried by the

shafts 21, 26, 30, and 32, and that the respective rolls of each pair are located one above the other, while one pair of rolls is located close to the end of the arbor. This arrangement of feed rolls will prevent the tail end of a supply of wire from whipping prior to its reaching the rotating arbor through which it is to be fed.

In accordance with the provisions of the patent statutes I have described the principles of operation of my invention, together with the apparatus which I now consider to represent the best embodiment thereof; but I desire to have it understood that the device shown is only illustrative and that the invention may be carried out by other means and applied to uses other than those above set out.

I claim:—

1. A wire straightening machine comprising a base, a wire straightening unit, a wire feed unit, means for independently removably securing each of said units to the base, and means other than the securing means for accurately aligning said units.

2. A wire straightening machine including a base, a breaker unit, a wire straightening unit, a wire feed unit, means for independently removably securing each of said units to the base, and means other than the securing means for accurately aligning said units.

3. A wire feed for a wire straightening machine and including a pair of wire feed rolls, a driving member for each of said rolls, said members being located on the same side of said rolls and means for relatively changing the positions of said members, one of said members having a path of movement parallel to the plane occupied by the other of said members.

4. A wire feed for a wire straightening machine including a plurality of pairs of wire feed rolls, means for driving one of the members of each pair independently of the support for the other and including a single member for driving one member of each of a plurality of said pairs.

5. A wire feed for a wire straightening machine including a plurality of pairs of wire feed rolls, driving members for said rolls, means for adjusting the relative positions of members of each pair of rolls, the driving member of one roll of each pair being located parallel to the path of adjusting movement of the other of said pairs, a common gear for driving one roll of each of said pairs, and means driven by said gear for driving the other roll of each of said pairs.

6. A wire feed for a wire straightening machine comprising a housing closed at opposite ends and having openings in its opposite side walls for sliding bearings, sliding bearings fitted within said openings to maintain them in closed condition, thereby constituting an oil-tight housing in different adjustable positions of the feed roll, feed roll shafts ad-

justably mounted in said bearings, intermeshing gears located on said shafts within said housing, and means for driving said shafts.

7. A wire straightening machine comprising a frame constituting a housing, feed roll shafts rotatably mounted in the walls of said housing, a trough located outside of the housing, a cap for closing said trough, and intermeshing driving gears located within said cap and trough, one of said gears being secured to one of said feed roll shafts.

8. A wire feed for wire straightening machines including a plurality of pairs of wire feed rolls, the axes of one roll of each pair being located in one plane, the axes of the remaining rolls being located in a second plane, a drive shaft located in one of said planes, means operatively connecting the drive shaft to the feed rolls located in the same plane therewith, a counter shaft located in the other of said planes, means operatively connecting the counter shaft to the feed rolls located in the same plane therewith, and means for operatively connecting the counter shaft to the drive shaft.

9. A wire feed for wire straightening machines including a plurality of pairs of wire feed rolls, a drive shaft and a counter shaft located in different horizontal planes, means for operatively connecting one roll of each pair of feed rolls to the drive shaft, means for operatively connecting the remaining roll of each pair of feed rolls to the counter shaft, and means for operatively connecting the counter shaft to the drive shaft.

10. A wire feed for wire straightening machines including a plurality of pairs of wire feed rolls, a drive shaft and a counter shaft located in different horizontal planes, means for operatively connecting one roll of each pair of feed rolls to the drive shaft, means for operatively connecting the remaining roll of each pair of feed rolls to the counter shaft, the respective connecting means being located in different vertical planes, and means for operatively connecting the counter shaft to the drive shaft.

11. A wire feed for wire straightening machines including a plurality of pairs of wire feed rolls, a drive shaft and a counter shaft located in different horizontal planes, means for operatively connecting one roll of each pair of feed rolls to the drive shaft, means for operatively connecting the remaining roll of each pair of feed rolls to the counter shaft, the respective connecting means being located in different vertical planes, means for operatively connecting the counter shaft to the drive shaft, and means for changing the relative positions of the respective feed rolls in each pair.

12. A wire straightening machine comprising a frame including a housing, a pair of feed rolls rotatably mounted in the walls of said housing, and means for adjusting one of

said shafts relative to the other, said means including openings in said walls, shaft bearings slidable in said openings, means for automatically adjusting said bearings in one direction, and means for manually adjusting said bearings in the opposite direction.

13. A wire straightening machine comprising a frame including a housing, a pair of feed roll shafts rotatably mounted in the walls of said housing, and means for adjusting one of said shafts relative to the other, said means including openings in said walls, shaft bearing blocks slidable in said openings and having flanges for closing the openings in all positions of the blocks, means for automatically adjusting said bearings in one direction, and means for manually adjusting said bearings in the opposite direction.

14. A wire straightening machine comprising a frame including a housing, a pair of feed roll shafts rotatably mounted in the walls of said housing, means for adjusting one of said shafts relative to the other, said means including openings in said walls, shaft bearings slidable in said openings, means for independently automatically adjusting said bearings in one direction, and means for uniformly adjusting both of said bearings in the opposite direction.
